OTHER PUBLICATIONS

Certificate of Examination for related Australian Design Application No. 201616145, Feb. 1, 2017, 2 pages.

Primary Examiner — Kevin K Rudzinski*Assistant Examiner* — Paul D Bohannon(74) *Attorney, Agent, or Firm* — Benjamin C. Armitage; Billon & Armitage(57) **CLAIM**

The ornamental design for garment collar, as shown and described.

DESCRIPTION

FIG. 1 is a front view of a garment collar showing my design; and,

FIG. 2 is a rear view thereof.

The broken line showing of a shirt in the drawings is for the purpose of illustrating environmental structure and forms no part of the claimed design.

1 Claim, 2 Drawing Sheets(56)
